CONCRETE INSERT

Filed Oct. 5, 1929

UNITED STATES PATENT OFFICE

LOTHAR R. ZIFFERER, OF COLUMBIA, PENNSYLVANIA; MABEL C. ZIFFERER, HARRY E. CHAMPION, AND H. NELSON ALBRIGHT, EXECUTORS OF SAID LOTHAR R. ZIFFERER, DECEASED, ASSIGNORS TO COLUMBIA MALLEABLE CASTINGS CORPORATION, OF COLUMBIA, PENNSYLVANIA, A CORPORATION OF NEW YORK

CONCRETE INSERT

Application filed October 5, 1929. Serial No. 397,479.

This invention relates to a concrete insert adapted to support an adjustable fastening means; more particularly, the insert is of the type in which the body is formed of two complementary parts between which is a protected chamber. The present invention is concerned with various features which adapt the two parts of the insert for mutual cooperation whereby their construction, assembly and installation is facilitated, and whereby a more satisfactory operation when placed in service, is assured. The insert is adapted to permit the insertion and removal of nuts when in situ so that it is adapted for use with bolts of various sizes. A suggestive embodiment of my invention is set forth in the accompanying drawings, wherein—

Figure 1 is a vertical longitudinal section through the insert shown in its position adjacent form boards prior to the removal thereof from the concrete casting,

Fig. 2 is a top plan view of the insert,

Fig. 3 is a bottom plan view thereof,

Fig. 4 is a central vertical section through the insert and surrounding concrete casting, a pipe hanger being supported therefrom,

Fig. 5 is a view in elevation of one end of the insert.

Fig. 6 is a transverse section therethrough on the line 6—6 of Fig. 2,

Fig. 7 is a fragmentary detail in section of the end wall taken on the line 7—7 of Fig. 6,

Fig. 8 is an inverted plan of a nut adapted to be used with said insert, and

Fig. 9 is a sectional detail showing a modified form of supporting member attached to said insert.

The body of the present insert consists of two complementary metal sections 10 and 11 which are substantially alike. Each section has a vertical side wall constituted by vertical portions 12 and 13 connected by a lateral offset 14, the construction being such that the wall portions 12 which occupy a lower position are spaced further apart than are the upper wall portions 13. The ends of the insert sections are formed by lower wall portions 15 which are connected to upper curved wall portions 16 which curve inward

ly and then outwardly to merge with the top wall 17 and end flanges 18 which project longitudinally therefrom. Lateral flanges 19 are also preferably provided on the top wall 17, said flanges 19 being connected to the upper vertical side wall portion 13 and the lateral offset 14 by means of side webs 20. The curved end wall portions 16 may be used to receive reinforcing rods 41, which may be thereby spaced from one another, and from the form boards 28 before the concrete is formed.

At the lower end of the wall portions 12 and 15, each section is provided with a horizontal plate or flange 21 provided with a long recess 22 on its inner side, the adjacent recesses 22 in the assembled insert uniting to form a slot 23 for the introduction of a nut 37 and a bolt 24 into the insert. At each end the bottom plate 21 is preferably continued to form a flange 25 and adjacent this flange lateral ears 26 are provided which are preferably bifurcated for the reception of nails by means of which the insert may be positioned upon the form boards 28 prior to pouring the concrete.

The lower end wall portions 15 of the section 10 carry inwardly extending tongues 29 which are provided with vertically extending heads 30 which are adapted to be hammered inwardly to engage lugs 31 which are formed on the adjacent lower end wall portions 15 of the section 11. It will readily be understood that by means of the tongues and heads 29 and 30 and the lugs 31, the two sections 10 and 11 may readily be permanently united into a unit.

The top wall 17 of the section 10 is provided on its inner side with a relatively thin flange 32 which is adapted to become seated in a corresponding recess in the top wall 17 of the section 11 so that the fluid concrete is prevented from flowing into the interior of the insert through the line of join between said top wall portions 17. The curved end portions 16 and the vertical wall portions 15 of the section 10 are provided along their innermost edges with a small flange 33 which engages the inner side of the corresponding end wall portions of the section 11 for the same

purpose. If desired, the flanges 33 may make a tight or drive fit with the section 11 and assist the tongues 29 and associated parts in holding the sections 10 and 11 together.

As will readily be understood from the transverse sectional view of the insert shown in Fig. 6, the interior of the insert comprises a relatively broad lower chamber 34 which opens into a narrower upper chamber 35. As seen in Fig. 1 the lower chamber 34 extends practically the whole length of the insert while the upper chamber 35 is substantially shorter owing to the curvature of the wall portions 16. The inner surfaces of the top walls 17 are slanted slightly in such manner that the maximum vertical clearance within the chambers 34 and 35 is along the medial line. This is for the double purpose of providing for proper draft in the making of the moulds from which the sections are cast and for supporting the nut and bolt in an equalized manner as best shown in Fig. 6. When the bolt is screwed in so that its end abuts the top wall of the insert, it will be centered automatically, its axis being then coincident with the medial line.

The inner surfaces of the bottom plates 21 preferably slope downwardly toward the medial line. Along the line of junction between these surfaces and the inner surfaces of the side wall portions 12 are provided longitudinal series of protuberances 36 preferably of arcuate configuration. As shown in Fig. 8, the lower edges of the nut 37 are correspondingly recessed at 39 so as to engage therewith. The end of the opening in the nut 37 which is directed outwardly is preferably flared as shown at 40 for the easy insertion of the bolt thereinto. It will be understood that the nut 37 fits freely within the chamber 34 so as to move therealong. When the bolt 24 is screwed into the nut 37 to such an extent that the upper end of the bolt bears upon the roof of the chamber 35, or pressure is otherwise applied upon the nut 37 in a downwardly direction, the recesses 39 at the lower edge of the sides thereof adjacent the side wall portions 12 engage the protuberances 36 so that lateral movement of the bolt 24 and the load carried thereby is prevented. It will be understood that when a bolt of different size is to be supported, a nut of the same outside dimensions is employed, the hole and threading of such nut being appropriate to receive the latter bolt. For the purpose of permitting ready removal and replacement of the nut 37, the side wall portions 12 and 13 are provided with an intermediate bellied portion 38 which extends from a level above the protuberances 36 to a level slightly above the normal position of the lateral offset 14. Said bellied portion does not extend to the ends of the chamber 34, so that when the nut is moved to either end, the bolt may readily be inserted

therein. In this position the nut is incapable of being rotated, owing to the relatively snug fit with the walls 12, and is prevented from excessive vertical movement by the lateral offset 14.

In use the portions 10 and 11 are assembled together as a unit and the lower face thereof applied to the form boards and attached thereto by means of nails passed through the slots in the ears 26. The reinforcing rods 41 may be positioned within the curved end walls 16 and the concrete is then poured. The concrete is prevented from passing into the chambers 34 and 35 by the flanges 32 and 33. After the concrete is set the form boards 28 are removed and the insert is ready for use when the concrete has acquired sufficient strength to take the load desired.

To apply a load on the insert, a nut 37, having a threaded opening of the necessary size, is inserted edgewise through the slot 23 into the space between the bellied portions 38. It is turned around therein so as to direct the face, having the recessed edges 39, downwardly so that said recesses may co-operate with the protuberances 36 at the join of the sides 12 and the bottom plate 21. In order to insert the bolt 24 in the nut 37, the latter is moved to one end of the chamber 34, where its freedom of movement is substantially curtailed, being in close proximity to the one end 15, the sides 12 and the lateral offsets 14. After the bolt 24 is threaded into the nut 37, the latter is moved along the chamber 34 to the desired location, in which it is held by engagement of the recesses 39 with the protuberances 36. The bolt 24 is preferably screwed into the nut 37 until the upper end thereof meets the sloping top walls 17 which direct said end to a central position. When the bolt 24 seats firmly in the apex of said sides, the nut 37 is held immovable on the lower faces 21 by the engagement of the recesses 39 and protuberances 36.

In the modification shown in Fig. 9, I have shown an adapter, having an upwardly extending threaded stud 42, which is not intended to extend into the upper chamber 35, but merely securely engages the nut 37. This adapter is also provided with a shoulder 43 which firmly engages the flanges 21 and thereby holds the nut firmly seated upon the upper side thereof. Owing to the engagement between the protuberances 36 and the recesses 39 of the bolt, movement of the latter is effectively prevented. Below the shoulder 43 the adapter is provided with an internally threaded socket 44, into which may be screwed a bolt or other device (not shown). By the use of some such fitting as this adapter, it is possible to support hangers, for example, where screw threads are of a size or style forbidding direct connection with the nut within the insert.

I claim:

1. A concrete insert having a body composed of two parts providing between them an elongated chamber to which access is provided by an elongated slot through the insert base, projecting bendable tongues provided with heads on the edges of the ends of one part, lugs on the edges of the ends of the other part, said tongues being bendable to cause said heads to engage said lugs and draw the parts into permanent unitary relation.

2. A concrete insert having a chambered body of two parts with abutting edge portions and an elongated countersunk flange projecting over the lines of abutment adapted to center the one part relative to the other, and co-operating means integral with the two parts and independent of said flanges adapted to interlock the body parts in unitary relation.

3. A concrete insert having a body within which is an elongated chamber the side walls of which are relatively close and far apart in their upper and lower regions respectively, there being in the insert base an elongated slot affording access to the chamber and the side edges of the slot providing opposite ledges on which a nut is adapted to be supported, the top wall of the chamber being oppositely inclined to center and laterally support a bolt end which is entered through the slot.

4. A concrete insert having a body within which is an elongated chamber provided with a slotted opening in its base, the chamber having a maximum vertical dimension extending centrally of its width, and the walls defining the base opening being slanted internally towards the slot through which a bolt is adapted to enter for threaded engagement with a nut supported upon the walls adjacent the slot, the bolt end being engageable with the chamber top with which it cooperates to derive support against lateral movement.

5. A concrete insert having a body of two connected parts with interfitting meeting edges extending medially of the body within which is an elongated chamber having its top and bottom provided with oppositely slanting surfaces such that the maximum vertical clearance is along the medial line, there being formed in the body bottom an elongated slot through which a bolt may pass to engage with a nut confined within the chamber, the bolt end being itself engageable with the top surface of the chamber to derive support therefrom.

6. A concrete insert having a chambered body, internal flanges adapted to engage the underside of a nut to support same, and define an opening whereby said nut and a bolt may be introduced, said body being bellied

intermediately of its ends to permit the nut to be rotated therein.

7. In combination, a concrete insert having a chambered body comprising nut supporting flanges, side and top walls and oppositely inclined projections on said flanges, a nut resting on said flanges provided on its underside with inclined recesses adapted to receive said projections, and a bolt member threaded into said nut to engage the top wall and firmly seat and center said nut on said flanges.

8. In combination, a concrete insert having a chambered body comprising nut supporting flanges and a nut adapted to rest thereon, means cooperating with said flanges adjacent ends of the chambered body in which the nut is adapted to be held when a bolt member is being inserted in said nut, the nut being provided on its underside with an unthreaded flare to facilitate the entrance of said bolt member.

9. In combination, a concrete insert having a chambered body comprising nut supporting flanges, a nut within said body supported on said flanges, and a supporting member screwed into said nut and provided with a shoulder bearing upon the outer surface of said flanges.

10. In combination, a concrete insert having a chambered body comprising nut supporting flanges, said flanges carrying projections on their inner sides, a nut within said body supported on said flanges and provided with recesses adapted to receive said projections, and a supporting member having a bolt portion screwed into said nut and provided with a shoulder bearing upon the outer surface of said flanges so as to hold said projections in the recesses and thus prevent movement of the nut within said body.

In testimony whereof, I have hereunto set my hand this 30th day of August, 1929.

LOTHAR R. ZIFFERER.
